UNITED STATES PATENT OFFICE.

GUSTY L. MILLER, OF UNIOPOLIS, OHIO.

WIRE-FENCE MACHINE.

SPECIFICATION forming part of Letters Patent No. 624,520, dated May 9, 1899.

Application filed February 13, 1899. Serial No. 705,403. (No model.)

To all whom it may concern:

Be it known that I, GUSTY L. MILLER, a citizen of the United States, residing at Uniopolis, in the county of Auglaize and State of Ohio, have invented certain new and useful Improvements in Wire-Fence Machines; and I do hereby declare that the following is a full, clear, and exact description of the same, reference being had to the annexed drawings, 10 making a part of this specification, and to the letters of reference marked thereon.

The present invention has for its object to provide a simple and effective machine to be used for the construction of wire fences in connecting the stay-wires to the line-wires by looping or twisting them around the same, provision being made for the easy manipulation of the machine when adjusting it from one line-wire to the other after the loop has 20 been completed and moving it along the line-wires as each stay-wire is completed.

The invention consists in a machine constructed substantially as shown in the drawings and hereinafter described and claimed.

Figure 1 of the drawings is a side elevation of the machine, showing it in operative position on the line-wires of the fence; Fig. 2, a top plan view thereof; Fig. 3, a detail perspective view of the twisting device removed 30 from its bearing; Fig. 4, a horizontal section taken on line 4 4 of Fig. 2; Fig. 5, a top plan view showing the twisting mechanism or device thrown back from contact with the line-wires for the purpose of moving the machine vertically or horizontally.

In the accompanying drawings, A represents the usual horizontal line-wires, and B the vertical stay-wires, connected thereto by looping or twisting them around the same. 40 A standard C is connected to the line-wires by means of the notched blocks *a*, with which said wires engage, and is adapted to be moved along the line-wires as circumstances require. To this standard C is connected the arm D by means of the pivoted link-bars E F, the link-bar E being adjustably connected to the stay G, which is pivoted to the standard. The link-bar E is connected to the stay G by means of a removable pin *b*, engaging with a 50 hole in the link-bar and one of a series of holes *c* in the stay.

Upon the arm D are suitable gear-wheels

I, which mesh with each other, each wheel having a grooved friction-roller H, between which the line-wire extends. A crank-handle J connects with the shaft of one of the gear-wheels I, and by turning the crank-handle the machine can be moved along the line-wires as the stay-wire is completed, and thus bring it in position to commence the next 60 stay-wire. When the loop of the stay-wire is completed around one line-wire, the wire-twisting mechanism is moved to the next line-wire by sliding it vertically upon the T-shaped guide K, projecting from the standard C, a 65 suitable bracket L, having a correspondingly formed T-shaped groove, fitting the T-shaped guide.

The grooved friction-rollers I may be brought in position to engage with any one 70 of the line-wires by changing the vertical position of the arm D as circumstances require. This is accomplished by removing the pin *b* and adjusting the height of the arm D, which is held in its adjusted position by replacing the pin *b* and engaging it with the 75 hole in the stay G coming opposite thereto.

The twisting mechanism is supported in a frame M, which frame is pivotally connected to the grooved bracket L to admit of the frame, 80 with its mechanism, being swung out of operative position, as shown in Fig. 5 of the drawings.

The wire used for the stays is contained on a spool N, eccentrically connected to a gear-wheel O, which meshes with a similar gear-wheel P. The gear-wheel P has rigidly connected thereto or cast therewith a bevel-pinion R, and with this pinion engages a similar pinion S, the shaft *e* thereof having a crank-handle T for turning it. A spring-actuated dog *f* is adapted to engage a depression or socket *g* in the inner face of the pinion S, as shown in Fig. 2 of the drawings. In making the loop of the stay-wire over the line-wire the dog is raised out of the depression or socket, which will allow the pinion to make a complete revolution, at which point the dog by action of the spring *h* will automatically engage itself with the depression or socket 90 and prevent the pinion from turning beyond the complete revolution, which revolution is sufficient to complete the loop or twist. The gear-wheel O has a slotted hub *i*, containing 95 100

a friction-pulley *k*, over which the stay-wire passes, as shown more clearly in Fig. 3 of the drawings, said wire passing out through the end of the hub. A ring *l* is secured on the 5 end of the hub or formed with it, as preferred, and has a yoke *m* on line with the slot *n* of the hub, which yoke is adapted to embrace the line-wire, as shown in Fig. 1 of the drawings.

The herein-described machine provides a 10 very practical and effective means for securing the stay-wires to the line-wires of a fence and is capable of both vertical and longitudinal adjustment along the line of fence in constructing the same.

15 Having now fully described my invention, what I claim as new, and desire to secure by Letters Patent, is—

1. In a wire-fence machine, a longitudinally-movable standard provided with means 20 for detachably connecting or engaging the line-wires thereto, a vertically-adjustable arm connecting with the standard, gear-wheels connecting with the adjustable arm and provided with friction-rollers between which one 25 of the line-wires extends, a crank-handle for turning the gear-wheels, and a wire twisting

or looping device adjustably connected to the standard, substantially as and for the purpose set forth.

2. In a wire-fence machine, a longitudinally-movable standard with which the line-wires are detachably connected, a swinging frame vertically adjustable upon the standard and carrying means for twisting or looping the stay-wires around the line-wires, and an 30 arm carrying gear-wheels with friction-rollers and means for turning said wheels, link-bars pivotally connected to the ends of the arm and to the standard, and a stay pivotally connected to the standard and adjustably connected to the upper one of the link-bars, whereby the arm is capable of vertical adjustment and held in its adjusted position, substantially as and for the purpose described.

35 In testimony that I claim the above I have 45 hereunto subscribed my name in the presence of two witnesses.

GUSTY L. MILLER.
